CHARLES M. STROUD, OF MINNEAPOLIS, MINNESOTA, ASSIGNOR OF ONE-HALF TO
LESLIE H. FAWKES, OF MINNEAPOLIS, MINNESOTA.

OIL-BURNING APPARATUS.

Application filed February 16, 1927. Serial No. 168,619.

This invention relates to liquid fuel burning apparatus and is an improvement over that form of burning apparatus shown in my pending application, Serial Number 5 99,956, filed April 5, 1926.

A general object of the invention is to provide improved means for mixing the air and the oil, and for projecting the same through the apparatus in a direction of the 10 flame orifice, in a manner to obtain thorough atomization of the oil, and to reduce sooting to the minimum.

Other objects of the invention are to provide an air mixing device as a tubular element, forming a continuation of the air intake orifice, and having an extension arranged to discharge downwardly into the casing; to direct air mixture so that a sheet-like discharge of the same is had which extends substantially entirely transversely 20 across the casing; to provide means whereby, during normal burner operation, that is after the burner is started, the oil is preheated by being discharged against a hot wall, to be spread along the wall and to be atomized as it is discharged; to provide means whereby the air is also pre-heated and spread and is made to pass through a sheet of flaming oil; to arrange the delivery end of the mixing 25 and spreading member in relation to the bottom of the casing or pot so that a maximum surface area at the bottom of said casing is provided on that side toward which the ignited mixture is discharged; to provide means to prevent fire from reaching the 30 over-flow pipe and to prevent burning oil from passing into or partly through the over-flow pipe; to provide a guard which also prevents sooting at the intake end of the 35 over-flow passage; to provide a tubular mixing chamber element as a continuation of the air intake pipe or orifice, which can be easily detached for purposes of cleaning; to provide an arrangement whereby the 40 point of discharge from the mixing chamber is at a level below the air intake conduit; to provide means for delivering oil into the extension to be spread across that face nearest the flame orifice of the pot; to provide means for discharging the oil downwardly into said extension; to provide a device in which a tubular oil and air mixing 45 and delivery tube forms a depending baffle

plate transversely dividing the burner casing, with the front wall of the tubular casing 55 providing the baffle and the whole structure providing a guard for the oil over-flow as above set forth; to provide an air intake pipe having its delivery end flared inwardly and divergent toward the vertical side walls 60 of the casing for spreading the air forwardly and laterally; and to provide a transversely and vertically curved discharge spout providing a flame orifice adapted to deliver 65 downwardly into the furnace, and leading from the end of the casing, the walls of said spout extending entirely across the pot or casing and discharge chamber.

Features of the invention include, all the 70 details of construction, the various shapes and arrangement of the parts, along with the manner of assembling the parts, and particularly the manner of assembling and connecting the tubular oil and air mixing chamber element in relation to the air delivery 75 end of the air intake pipe, to the flame orifice, as well as the arrangement of the oil delivery duct and connections for delivering oil thereto.

Advantages of the device will be disclosed 80 in the description of the drawings which forms a part of this application and in said drawings:

Figure 1 represents a side elevation of the 85 device applied to a furnace door, and showing the furnace door in section;

Figure 2 is a vertical longitudinal section;

Figure 3 is a plan section substantially on line 3—3 of Figure 2;

Figure 4 is a vertical cross-section substantially on line 4—4 of Figure 2; and

Figure 5 is a detail end view of the tubular mixing or vaporizing chamber.

The numeral 1 designates the casing or pot which has generally a rectangular cross-section as shown in Figure 4 although this cross-sectional configuration may be modified within certain limits without departing from the spirit of the invention. This casing has a flame discharge orifice 2 formed to discharge downwardly, said orifice being partly defined by a hood-like extension of the casing. The walls of this hood-like extension, which walls cooperate in forming the downwardly directed flame discharge 105 orifice, are vertically and transversely

curved, and the spout or hood extends entirely across the chamber so that its vertical side walls are a continuation of the vertical side walls of the pot and its top wall is a continuation of the top wall of the pot.

The wall 30 of the casing slants outwardly and has its upper edge spaced from the top wall substantially as shown.

The casing has a flange 10 and also has an extension 11 which is normally disposed at the outer side of the door 5, the flange 10 and the door being traversed by suitable bolts to secure the device substantially as shown in Figure 1. The top and vertical side walls of the extension are continuations of the corresponding walls of the casing. The height of the extension is, therefore, less than the height of the casing and the extension is arranged at an upper level substantially as shown. Connected with the extension substantially as shown in Figure 3 is an air intake pipe 7 having its delivery end flared inwardly and divergent toward the vertical side walls of the pot or casing as at 8 for spreading the air laterally toward and along vertical side walls. The details thus far set forth are substantially those shown in the pending application above referred to.

30 The salient feature of the present device is the tubular mixing element as a continuation of the air intake conduit or of the extension 11, which may be considered as a portion of the air intake conduit. This device is removably fitted within the portion 11, and has an extension 20 arranged to discharge downwardly into the casing. The horizontal portion 21 is shaped and fitted substantially as shown in Figure 2, and has 35 a bottom wall 23 resting upon the bottom wall of the extension 11. Suitable screws indicated in dotted lines at 25 hold the mixing chamber against accidental displacement. A tubular mixing element is arranged so that it discharges at a level below 40 the air intake conduit, by which means the air and oil, mixed and flaming, are carried to the bottom of the casing there to be discharged in a direction generally toward the bottom of the casing and toward the outer 45 vertical wall 30 of the casing. The mixing element is curved at its upper side as at 31 so as to reduce friction and direct the air downwardly into the downwardly-reaching 50 extension 20.

The discharge orifice 35 of the mixing element is of a dimension substantially as shown, and it will be noted that, in this instance, the area of this orifice is greater 55 than the horizontal cross-sectional area of the extension.

It will also be noted that the cross-sectional area of the portion 21 is greater than that of the extension 20 whereby the velocity 60 of air is reduced in the extension or mixing

leg, to obtain the proper atomization, mixing and flame spreading.

Means for delivering oil into the extension is provided, and, in this instance, the delivery is in a downward direction. The 70 element is bored as at 36 to provide for this oil delivery, in this instance, in a downward direction, and the upper end of the bore is screw-capped as at 37, and the cap may be removed to clean the conduit. By this 75 arrangement, the oil is flowed and spread upon the inner side of the wall 39, and inasmuch as this wall is highly heated during operation of the burner, a high degree of vaporization, mixing and flaming is obtained within the tubular mixing element. The angular relation of this upright bore 80 may be slightly changed, and it may be sometimes desirable to direct the oil in a direction more toward the rear wall 40 of 85 the tubular element. In the structure shown, the oil is discharged substantially at the level of the air intake and, therefore, opposite the horizontal portion 20 of the tubular mixer.

90 It will be noted that as a result of the arrangement, the oil is pre-heated and is discharged upon the inner surface of the hot forward wall of the mixing element. The oil is thus highly atomized as the result of its being flowed upon the surface as above mentioned. The air is also pre-heated and spread so that the sheet of flame issues from the orifice 35 entirely across the casing. It will be noted that the delivery 95 end of the mixing and spreading element, that is the orifice 35, is arranged rearwardly of the wall 30 so that the maximum surface area at the bottom of the pot is provided, on that side toward which the ignited mixture is traveling. It is to be understood that the fire flashes back to the point of delivery 100 of the oil and burning takes place from that point outwardly. The angle of the wall 30 may be changed under certain conditions but the burner has at present been found to operate best with the angular relation shown in the drawings.

105 The wick is shown at 32, and is supported by wires 33.

110 The rear wall 40 of the extension 20 is provided with a lug 50 to space the wall 40 from the rear wall 51 of the casing or pot, and the lower edge of the wall 40 is scalloped as at 42 to provide for underflow of oil to the over-flow pipe 60.

115 Oil is delivered to the conduit 36 through a horizontal pipe 55 which is suitably connected by threads with an orifice 56 which communicates with the conduit 36. An elbow 57 connects the pipe 55 with the pipe 58 which latter pipe extends downwardly through the extension 11 and lower wall of the air intake pipe.

120 It will be noted that the openings 43 are 130

provided in that wall nearest the flame orifice, and that the openings are substantially at the level of the air intake conduit. It will be further noted that the discharge opening 5 of the extension is of greater area than the cross-sectional area of the extension, and it will be further noted that the air intake or horizontal end of the tubular element is substantially of the same cross-sectional area 10 as the air intake conduit and of a greater cross-sectional area than the downwardly directed portion 20.

The oil pipe passes through the air intake conduit in direction of the inward travel 15 of the air and delivers into the oil conduit in a direction substantially perpendicular thereto. The delivery thus takes place in a a horizontal direction and the oil in the pipe 55 and in that portion of the pipe 58 which 20 extends within the casing is pre-heated, inasmuch as when the burner is in operation, heating takes place considerable distance outwardly from the downwardly extending portion 20 in direction of the incoming air 25 and above the point of introduction of the oil.

In assembling, the pipe 55, carrying the elbow 57, is screwed into the orifice 56. The horizontal extension of the tubular mixing 30 element is then properly positioned and the screws 25 introduced, after which the pipe section 58 is thrust upwardly and screwed to the elbow 57. Extending outwardly from the front wall 51 of the casing is a return 35 oil pipe 60 and this pipe communicates with the interior of the pot at a level above its bottom but below the air intake substantially as shown, see Figures 2 and 4. The extension 20 thus forms a guard to prevent fire from reaching the over-flow pipe and to prevent passing of flame into the pipe. The guard also prevents sooting at the intake end of the over-flow pipe or passage.

In order to prevent eddying, openings 43 45 are provided and are arranged substantially as shown, at the level of the air intake pipe.

A fan casing 80 is herein shown as an integral part of the air delivery pipe 7. 50 This, however, is not necessary. An air intake pipe 84 leads laterally from the casing 80, and this pipe has its intake end 85 adjacent the door and spaced outwardly therefrom at the outer side of the door. This 55 device forms no part of the present invention except generally as means for supplying air and oil to the burner; the oil reservoir is shown at 90, control valve at 91, and a trap for the oil return pipe at 92.

In the operation of the device, the control 60 valve is opened to allow a comparatively small layer of oil to flood the bottom of the pot, this amount generally being a layer from one-sixteenth to one-eighth of an inch 65 in thickness. The wick 32 is now lighted,

to start the burning of the film of oil on the bottom of the pot, ignition, combustion and flaming thus taking place in the ignition and combustion chamber, of which, after starting, the extension 21 may be considered a part, inasmuch as flaming takes place at point of introduction of the oil. After the oil is ignited the blower is turned 70 on and the oil is then fed in the proper quantity. 75

It will be noted that in the normal operation of the burner, the fire flashes back to the place at which the oil is introduced, and burning takes place at the discharge orifice. As the result of the arrangement 80 herein, the oil is pre-heated and is discharged on the hot or forward wall of the mixing chamber. The oil is atomized as it is discharged and also as it is flowed upon the inner side of the hot wall. The air is 85 also pre-heated and spread and is made to pass through the sheet of flame. The delivery end of the mixing and spreading element is arranged so that the maximum surface area at the bottom of the pot is provided on that side toward which the ignited 90 mixture is traveling.

It will be noted that the cold air rushing into the tubular element passes through the sheet of flame. It will also be noted that the flared air intake spreads the air transversely entirely across the casing so that the flaming mixture is delivered in a sheet extending entirely transversely across the casing, and this sheet-like flame is delivered 100 into the fire box of the furnace in a downward direction also as a thick sheet of flame.

The guard is arranged to prevent fire from reaching the over-flow pipe, and to prevent the passing into or partly through the over-flow pipe. The guard also prevents soot-ing at the intake end of the over-flow passage or pipe.

It will be noted that the oil and air 110 spreader is a unit casting, which can be easily and quickly removed for purposes of cleaning. It will be further noted that oil is delivered on both forward and rearward walls of the tubular element during a normal operation of the burner, it being understood that the angular relation of the oil discharge conduit may be changed within certain limits without departing from the spirit of the invention.

It will be further noted that the flange 10 extends entirely around the casing and that the openings 10^a for the fastenings are arranged in a novel manner. The two upper openings being arranged inwardly and being the ones by which the casing is suspended, and the lower openings 10^b being arranged at the corners for the purpose of drawing the casing inwardly against the door. By this relative arrangement of the openings, the flange is caused to positively 125 130 135

and evenly engage the outer surface of the door to virtually form a sealed connection. This is a feature of the invention.

I claim as my invention:

1. A device of the class described comprising a casing having a flame discharge orifice and a horizontal air intake conduit at that end opposite the orifice, a tubular element as a chamber and as a continuation of the air intake orifice having an extension arranged to discharge downwardly into the casing the point of discharge being below the level of the air intake conduit, means for delivering oil into the extension in a downward direction at a point substantially at the level of the air intake, an oil over-flow pipe communicating with the casing below the air intake, said extension being protectingly opposed to the intake end of the over-flow pipe.
  2. A device of the class described comprising a casing having a flame discharge orifice, and an air intake conduit at that end opposite the opening, said conduit extending transversely entirely across the casing, a tubular element as a mixing chamber and as an inward continuation of the air intake orifice and of substantially the same transverse dimension and having an extension arranged to discharge downwardly into the casing.
  3. A device of the class described comprising a casing having a flame discharge orifice and an air intake conduit at that end opposite the orifice, and a tubular element as a continuation of the air intake orifice having an extension arranged to discharge downwardly into the casing at a point below the air intake and orifice, said extension having openings through that wall nearest the flame orifice.
  4. A device of the class described comprising a casing having a flame discharge orifice and an air intake conduit at that end opposite the orifice, and a tubular element as a continuation of the air intake orifice having an extension arranged to discharge downwardly into the casing at a point below the air intake and orifice, said extension having openings through that wall nearest the flame orifice, and said openings being substantially at the level of the air intake conduit.
  5. A device of the class described comprising a casing having a flame discharge orifice and an air intake conduit at that end opposite the orifice, and a tubular element as a continuation of the air intake orifice having an extension arranged to discharge downwardly into the casing, the discharge opening of said extension being of greater area than the cross-sectional area of said extension.
  6. A device of the class described comprising a casing having a flame discharge orifice and an air intake conduit at that end
- opposite the orifice, and a tubular element as a continuation of the air intake orifice having an extension arranged to discharge downwardly into the casing, the discharge opening of said extension being of greater area than the cross-sectional area of said extension, and said tubular element at its air intake end being substantially of the same cross-sectional area as the air intake conduit. 70
7. A device of the class described comprising a casing having a flame discharge orifice and an air intake conduit at that end opposite the orifice, and a tubular element as a continuation of the air intake orifice having an extension arranged to discharge downwardly into the casing, said tubular element having an oil conduit leading downwardly into its extension, and an oil pipe passing through the air intake conduit and delivering to said oil conduit in direction substantially perpendicular thereto. 75
8. A device of the class described comprising a casing having a flame discharge orifice and an air intake conduit at that end opposite the orifice, and a tubular element as a continuation of the air intake orifice having an extension arranged to discharge downwardly into the casing, said tubular element having an oil conduit leading downwardly into its extension and an oil pipe passing through the air intake conduit and delivering to said oil conduit in direction substantially perpendicular thereto, the delivery taking place in horizontal direction and in direction of the travel of the incoming air. 80
9. In combination with a furnace door having an opening, a burner apparatus having a casing passing through the opening, said casing having a plate-like flange integral therewith and circumscribing the casing and acting as a stop to limit inward movement of the casing and to close the opening, said flange having openings, and bolts passing through said openings to secure the flange to the door, the upper and lower horizontal portions of the plate-like flange each having two openings, the openings of the lower flange portion being spaced a greater distance apart horizontally than the openings of the upper flange portion. 85
10. A casing having a flame discharge orifice and an air intake conduit, a tubular element within the casing as a mixing chamber and as an extension of the intake conduit, and having a portion leading downwardly to discharge and having an oil port for introducing oil thereinto, said air conduit extending entirely transversely across the casing. 90
11. A casing having a flame discharge orifice and an air intake conduit horizontally arranged at the upper part of the casing, a tubular element within the casing as a

mixing chamber and as an extension of the intake conduit, and having a portion leading downwardly and arranged to discharge adjacent the bottom of the casing and having an oil port for introducing oil thereto, said air conduit extending entirely transversely across the casing, and being of a form to provide a sheet-like flow of products passing therethrough.

10 12. A casing having a flame discharge orifice and an air intake conduit, a tubular element within the casing as a mixing chamber and as an extension of the intake conduit and having a portion leading downwardly, 15 and having front and rear walls, that wall of the extension nearest the flame orifice having a port for delivering oil into the downwardly leading portion, and said mixing chamber extending transversely entirely 20 across the casing.

13. A casing having a flame discharge orifice and an air intake conduit, a tubular element within the casing as a mixing chamber and as an extension of the intake conduit, 25 and having a portion leading downwardly and arranged to discharge generally in a direction towards the spout, and having a port for delivering oil into the downwardly leading portion, said mixing chamber extending 30 transversely entirely across the casing and being of a form to provide a sheet-like flow of the flaming mixed products, said tubular element having a portion removably fitted within said air intake conduit.

35 14. A casing having a flame discharge orifice and an air intake conduit spaced apart horizontally, a tubular element within the casing as an air intake extension, and having a downwardly leading portion opening 40 adjacent the bottom of the casing, and having an oil port for delivering thereto, said casing having an overflow orifice in the same wall with the intake conduit, the arrangement being such that the downward leading portion forms a guard for said overflow opening.

45 15. A device of the class described comprising a casing as a fire pot having a flame discharge orifice, and an air intake conduit leading thereto spaced apart lengthwise of the casing, a tubular element as a mixing chamber, and continuation of the intake conduit and having a downwardly directed portion including front and rear walls the 50 lower end of the rear wall extending substantially to the bottom wall of the casing and the lower end of the front wall spaced a greater distance thereabove, said tubular element extending entirely transversely across the casing and having an oil delivery port arranged to deliver into the downwardly directed portion, and means for supplying oil to said port.

55 16. A device of the class described comprising a casing as a fire pot having a flame

discharge orifice, and an air intake conduit leading thereto spaced apart lengthwise of the casing, a tubular element as a mixing chamber and continuation of the intake conduit, having a downwardly directed portion including front and rear walls, the lower end of the rear wall extending substantially to the bottom wall of the casing and the lower end of the front wall spaced a greater distance thereabove, said tubular element 70 extending entirely transversely of the casing and having an oil delivery port arranged to deliver into the downwardly directed portion, and means for supplying oil to said port, a portion of the means being 75 arranged in the horizontal intake conduit and overlying the downwardly directed portion of the mixing chamber.

17. A casing having a discharge spout at one end and horizontally arranged and spaced air intake conduit at the opposite end, both spout and opening being substantially the same level and at a level above the bottom of the casing, said air intake having its delivery end flared inwardly and divergent for spreading the air transversely, and a tubular element communicating with the air intake and having throughout the same area as the discharge end of the air intake conduit and having an extension directed 80 downwardly into the casing below the level of the flame discharge orifice, said tubular element constituting a mixing chamber and being formed to provide a sheet-like flow 85 of the fuel and air, and means for delivering oil into the tubular element.

18. A casing having a discharge spout and an air intake conduit, said air intake having its delivery end flared inwardly and divergent for spreading the air transversely, and a tubular element communicating with the air intake and being of the same area as the discharge end of the air intake conduit and having an extension directed 90 downwardly into the casing below the level of the flame discharge orifice, said tubular element constituting a mixing chamber and being formed to provide a sheet-like flow of the fuel and air, and means for delivering oil 95 into the tubular element.

100 19. A device of the class described comprising a casing as a fire pot having a flame discharge orifice, and an air intake conduit leading thereto, a tubular element as a mixing chamber, and as a continuation of the air intake and having a downwardly directed portion arranged to delivery adjacent the bottom of the casing, said tubular element extending entirely transversely across 105 the casing and being of a form to give a sheet-like character to the mixture before discharge, and said intake conduit being flared inwardly and divergently toward the tubular element, to spread the air transversely thereacross.

20. A device of the class described comprising a casing as a fire pot having a flame discharge orifice and an air intake conduit leading thereinto spaced apart lengthwise 5 of the casing, a tubular element as a mixing chamber and continuation of the air intake and having a portion extending downwardly and arranged to deliver adjacent the bottom of the casing, said tubular element extending entirely transversely of the casing and being of a form to give a sheet-like character to the mixture before discharge.

21. A device of the class described comprising a casing having a flame discharge orifice and an air intake conduit spaced apart lengthwise of the casing, a tubular element as a continuation of the air intake orifice and having an extension leading downwardly within the casing to discharge 15 adjacent the bottom thereof and formed to provide a discharge orifice at its lower end of greater area than the cross-sectional area of the tube element, means for delivering oil into the extension generally in a direction 20 towards its lower end in a manner to cause the oil to flow, the said element extending the entire transverse width of the casing, and said air intake conduit having its delivery end flared inwardly and divergent 25 toward said tubular element to spread the air entirely transversely thereacross before its entry into said element.

22. A casing having a flame discharge orifice, and an air intake conduit having its 30 delivery end flared divergently to spread the air transversely across the casing, a substantially L-shaped tubular element as a mixing chamber, having one arm removably fitted in the delivery end of the conduit and 35 having its opposite arm extending downwardly to deliver adjacent the bottom of the casing, and means for delivering oil into the tubular element.

23. A casing having a flame discharge orifice, and an air intake conduit having its delivery end flared divergently to spread the air transversely across the casing, a sub- 40

stantially L-shaped tubular element as a mixing chamber, having one arm removably fitted in the delivery end of the conduit and 50 having its opposite arm extending downwardly to deliver adjacent the bottom of the casing, and means for delivering oil into the tubular element, and said tubular element having a form adapted to obtain a 55 sheet-like flow of products.

24. A casing having a hood-like flame discharge orifice in one wall extending entirely transversely thereacross, and having an air intake conduit in the opposite wall also extending entirely transversely thereacross, both at a level above the bottom of the casing, said intake conduit having its delivery end flared divergently to spread the air transversely across the casing, a substantially 60 L-shaped tubular element as a mixing chamber extending also entirely transversely across the casing and having one arm removably fitted in the delivery end of the conduit, and having its opposite arm 65 extending downwardly to deliver adjacent the bottom of the casing generally in a direction toward the flame discharge orifice, and means for delivering oil into the downwardly extending arm.

25. A device of the class described comprising a casing as a fire pot having a flame discharge orifice and an air intake conduit, a tubular element as a mixing chamber, and continuation of the intake conduit and having a downwardly directed portion arranged to deliver adjacent the bottom of the casing and being of a form to give a sheet-like character to the mixture before discharge, said air intake conduit having its delivery 80 end flared inwardly and divergently for spreading the air transversely of the tubular element, said tubular element having a port arranged to deliver into said downwardly directed portion.

In witness whereof, I have hereunto set my hand this 14th day of February, 1927.

CHARLES M. STROUD.
